CLAIM

The ornamental design for a head rail mounting clip, as shown and described.

DESCRIPTION

FIG. 1 is a top perspective view of a head rail mounting clip oriented with respect to a portion of a head rail and blind set showing our new design;

FIG. 2 is an enlarged view of the clip shown in FIG. 2;

FIG. 3 is a front elevational view of FIG. 2;

FIG. 4 is a rear elevational view of FIG. 2;

FIG. 5 is a right side elevational view of FIG. 2;

FIG. 6 is a left side elevational view of FIG. 2;

FIG. 7 is a top plan view of FIG. 2; and,

FIG. 8 is a bottom plan view of FIG. 2.

The dotted line representation on FIGS. 1, 2, 7 and 8 are for information only, and form no part of the subject design.
